UNITED STATES PATENT OFFICE.

WILLIAM W. LASKER, OF BROOKLYN, NEW YORK, ASSIGNOR TO POWERS ACCOUNTING MACHINE COMPANY, OF NEW YORK, N. Y., A CORPORATION OF DELAWARE.

DESIGNATION-PRINTING MEANS.

1,388,271.

Specification of Letters Patent. Patented Aug. 23, 1921.

Application filed February 18, 1916. Serial No. 79,013.

To all whom it may concern:

Be it known that I, WILLIAM W. LASKER, a citizen of the United States, residing in Brooklyn, in the county of Kings and State 5 of New York, have invented certain new and useful Improvements in Designation-Printing Means, of which the following is a specification.

This invention relates to accounting machines in general and more particularly 10 to the class of tabulator printers coöoperating with perforated record cards.

With the tabulator printers in use, there are generally a plurality of groups of printers which, at one setting, will print the individual items of each card as it is passed through the machine, and the accumulation of such printer groups will simultaneously be actuated to accumulate the amounts of 20 such items, and then upon the passage through such machine of a so called total card, the machine will automatically shift its mechanism from the position of printing individual items to a position for printing 25 totals.

The present invention contemplates means whereby any one of the groups may be used as a designating group, whereby a designation character may be printed that is common to all the record cards of a certain series 30 being printed, which group at a certain setting may, without further manipulation, print the designation character when the first card is being passed through, will transfer 35 such character to the accumulator, discontinue the operation of the accumulating means after such first transfer, permit printing the same designation for the remaining cards of the series, and then upon the passage 40 through the machine of a total card again actuate the accumulating means to permit such accumulating means to transfer to the printing means and print with the totals the designation character which had been 45 transferred to the accumulator.

In the accompanying drawings, an arrester or anchoring means is illustrated which finds particular adaptation with the present arrangement but is equally advantageous 50 with all total taking mechanisms which anchoring means is adapted to anchor certain elements of the tabulator printers now in use until the total has been taken. An application claiming this anchoring 55 means separately is shown in my copending

application, filed Feb. 28, 1916, Serial No. 80,793.

These and other features, capabilities and advantages of the invention will appear from the subjoined detailed description of 60 one specific embodiment illustrated in the accompanying drawings in which—

Figure 1 is a side elevation of a machine equipped with the present improvement.

Fig. 2 is a fragmental front elevation of 65 the upper part of the machine.

Fig. 3 is a side elevation of a part of the action including portions of the present improvement.

Fig. 4 is a section on the line 4—4 of Fig. 3. 70

Fig. 5 is a rear elevation of the part shown in Fig. 4.

Fig. 6 is a front elevation of the essential parts constituting the present invention.

Fig. 7 is a fragmental detail showing the 75 setting mechanism in a released position as contrasted to the position shown in Fig. 3 in which the setting mechanism is disposed in anchoring position.

Fig. 8 is a fragmental detail showing the 80 means for connecting the total actuating means with the setting means forming the present invention.

Figs. 9 and 10 are fragmental views showing successive positions of the non-accumulating mechanism. 85

Figs. 11 and 12 are fragmental side and end elevations of the connection between the positioning pin and the total taking shaft.

Fig. 13 is a detached view of the slide of 90 the nonlatching mechanism.

In the embodiment shown, the following elements are substantially identical with those illustrated in my copending application, Serial No. 89534, filed April 7, 1916; a 95 plurality of groups of type carrying sectors 12 connected thereto, accumulator engagement segments 13 provided with gear teeth 14, accumulator wheels 15 for engagement with the gear teeth 14, shafts 16 on which 100 the accumulator wheels 15 are mounted, cam levers 17, cam slots 18 in such cam levers 17 being pivotally connected to the supports 19 on the main frame A, a reciprocable link 20 for each group of segments 13 pivotally connected to the levers 17 and extending forwardly therefrom, actuating lever engagement recesses 21 and 22 on said link 20, the recess 21 being formed in the upper edge 105 of the link 20 and the recess 22 in the lower 110

edge of the link 20, a link actuating lever 23 pivotally mounted on the shaft 24 journaled in the downwardly extending brackets 25 of the auxiliary frame 26, a pin 27 on said lever 23 adapted to engage the recess 21 and a pin 28 on the lever 23 adapted to engage the recess 22, a crank sector engaging lever 29 yieldably mounted on said shaft 24, and a crank sector 30 secured to the main actuating 10 shaft 31 of the printing and total taking mechanism.

The mechanism about to be described essentially forms the elements that coöperate with the foregoing main elements to produce 15 the results aimed to be obtained by the present invention.

Since the constituent elements forming the improved mechanisms for the several groups of sectors are substantially identical, but one 20 group will be described.

Forwardly of the actuating shaft 31 is situated the total taking shaft 32 on which is loosely mounted a bell crank lever 33 having an upwardly extending arm 34 and a 25 rearwardly extending arm 35, the end of the rearwardly extending arm 35 being connected to the link 20 by a spring 36. Forwardly of the connection of the spring 36 with the arm 35 is pivotally connected the 30 lower end of the link 37, the upper end having a slot 38 formed therein through which the pin 39 of the link 20 extends, thereby the slot-and-pin connecting the link 37 with the link 20. Fixed to the shaft 32 is the 35 lever 40 having a pin 41 on its free upper end extending across the front edge of the arm 34.

The rocking of the shaft 32, as formerly, 40 rocks the bell crank 33 to initiate the total taking operation. For automatically rocking the shaft 32, in the present instance, a lever 42 (Fig. 8) is fixed to the shaft 32 extending rearwardly therefrom, to the free rear end of which is pivotally connected the 45 link 43, the lower end of which link 43 is pivotally connected to the rearwardly extending arm 44 loosely mounted on the rod 45 secured in the lower part of the main frame A. Fixed to the arm 44 is the upwardly extending arm 48 and the downwardly extending ratchet arm 49. The arm 48 has at its upper end a lug 50 adapted to engage the lug 51 on the reciprocating link 52 which is pivotally connected at one end 50 to the upwardly extending arm of the pivotally mounted bell crank 53, the rearwardly extending arm of which bell crank 53 has a roller 54 thereon for engagement with the cam groove 55 of the cam 47. The reciprocating link 52 has a rod portion 56 at one end thereof (Fig. 11) extending through an opening formed in the lower end of the positioning pin 57. The positioning pin 57 is reciprocatingly mounted in the pin box 58 60 having a collar 59 between which and a

lower plate 60 of the pin box 58 a spring 61 is strained whereby such pin 57 is resiliently maintained in its raised position disposed above the pin box 58, as common in machines of this class, are positioned the die plate 62 and 63 respectively, between which the card to be analyzed will be positioned for analysis. Formed in the plates 62 and 63 are the openings 64 and 65 respectively for registration with the pin 57. The openings 64 and 65 are larger in diameter than the diameter of the pin 57 being large enough to permit the passage therethrough of the collar 66 formed on the pin 57.

The openings 64 and 65 and the collar 66 coöperate with one another so that three distinct positions of the pin 57 may be produced. This is done as follows: With every cycle, the pin box 58 is raised, thereby raising the pin 57 with it. If the card being analyzed is a record card, it will have no perforation to register with the openings 64 and 65 and thus the pin 57 will be obstructed in its upward movement by its extreme end coming in contact with the card; if the card is a total card, it will have a small perforation (Fig. 11) permitting the passage of the upper end of the pin 57, but obstructing the collar 66 from passage therethrough; and on the other hand, if the card is a stop card, or no card at all is located between the plates 62 and 63, free upper passages of the pin 57 is permitted so that its collar 66 may likewise pass therethrough.

After every rise of the pin box 58, the link 52 is reciprocated by the bell crank 53 being actuated by the cam 47. The position of the pin 57 will determine the path of movement of the lug 51 on the link 52 relative to the lug 50 on the arm 48. These relative positions are such that when the pin 57 is either in its extreme upper position or in its lowest position, the lug 50 will not be disposed in the path of movement of the lug 51 and consequently the actuation of the link 43 by the actuation of the arm 48 will not take place, but when the pin is in the intermediate position, that is, when the total card contacts with the collar 66 and thereby obstructs the pin 57 from further upward movement, the lug 50 will be disposed in the path of movement of the lug 51 whereupon the actuation of the link 52 by the bell crank 53 bringing the lug 51 into contact with an actuating lug 50, 110 will rock the arm 48 thereby rocking the arm 44 to actuate the link 43 which in turn by its connection with the total shaft 32 will actuate the same to initiate the total taking operation. For anchoring the total 115 taking shaft 32 in the total taking position until the operation is completed, the ratchet arm 49 when rocked downward by the actuation of the lug 50, will snap under the latch 67 which is fulcrumed to the downwardly 120 130

extending arm 68 formed on the rod 45 and resiliently maintained in anchoring position by the spring 69. The lower end of the latch 67 is provided with a pin 70 to be engaged by the finger 71 formed on the cam 47. Thus, the latch 67 will anchor the total taking shaft 32 in total taking position until the finger 71 in its cycle comes into contact with the pin 70 and disengages the latch 67 from the ratchet arm 49 together with the linkage connecting the total taking shaft 32 thereupon being immediately retracted to normal or non-total taking position by the spring 36 and the spring 72 which connects the arm 35 with the main frame A.

The mechanism so far described includes the action elements in operation when the mechanism is to be set in a normal condition, that is, to print the several items of the record cards, and simultaneously accumulating the amounts of the several cards on the accumulator wheels 15 so that at the required time, the total may be taken. The operation of the foregoing is substantially identical with that disclosed in my copending application, Serial No. 89534, filed April 7, 1916. In other words, according to the records of the record cards, when the individual items are being printed, the type sectors 12 will be set by suitable extension rods 74 (Fig. 1) which reproduce the records of the cards by coöperation with the perforations of the cards. Then the crank sector 30 having rocked forwardly to release the type sectors 12 and simultaneously withdrawn the accumulator wheels 15 out of engagement with the gear teeth 14 of the segments 13 on the advance movement of the type sectors 12, this being done by the engagement of the lever 29 by the sector 30, the link 37 being in raised position so that the recess 21 of the link 20 will be engaged by the pin 27 of the actuating lever 23, such engagement of the sector 30 with the lever 29 will rock the lever 23 so that its pin 27 will move the link 20 rearward, thereby rocking the cam levers 17 rearward which by their cam slots 18 will withdraw the accumulator wheels 15 out of the path of movement of the gear teeth 14.

Upon the return movement of the sector 30, the return engagement of the sector 30 with the lever 29 will rock the lever 23 to bring the accumulator wheels 15 into the path of movement of the gear teeth 14, so that the sector 30 also simultaneously retracting the type sectors 12 and segments 13, the records just printed will be accumulated by the accumulator wheels 15.

Then upon taking a total, the rocking of the total taking shaft 32 will by engagement of the pin 41 with the bell crank lever 33 draw downwardly the link 37 thereby drawing the link 20 downwardly so that the pin

28 of the lever 23 will enter the recess 22 of the link 20. Thereupon when the sector 30 moves forwardly, the segments 13 when released will engage the accumulator wheels 15 on their advance movement, the sector 30 by engagement with the lever 29 positioning the accumulator wheels 15 in the path of movement of the gear teeth 14. The accumulator wheels 15 in this operation are anchored against further movement when they are turned to their zero or clear position. Thus when the sector 30 thereupon returns, the engagement of the lever 29 thereby rocking the lever 23 to move the link 20 rearward, will thereby withdraw the accumulator wheels 15 out of engagement with the gear teeth 14 and withdraw them when in clear position, this operation serving to clear the machine ready for another series of cards.

The mechanism whereby, of a series of record cards, only the first item will have the designation character accumulated on its accumulator wheels, comprises means for setting the printing group to be used for printing the designation so that upon its initial actuation the printing of the first designation arm is permitted with the first card of the series being recorded and such designation accumulated on the accumulators, whereupon the accumulators of that group will be practically withdrawn from operation until the total is to be taken, and the actuation of the total taking means be permitted to again release the designation accumulators to permit the accumulated item to be printed with the total. The mechanism for so setting a printing group comprises essentially the vertically reciprocatable slide 75 guided in its vertical movement by the pin 76 secured to the auxiliary frame 26 and the shaft 77 mounted in the bracket 89, the upper end of the slide 75 having a recess 78 therein coöoperating with the pin 76 and a recess 79 at its lower end coöoperating with the shaft 77. On the edge of the rear lower portion of the slide 75 a series of ratchet teeth 80 are formed, and disposed above these ratchet teeth 80, the slide 75 is cut away to form the enlarged recess 81. Beyond the upper edge 82 of the recess 81, the stop plate 83 extends, such stop plate 83 having slot 84 (Fig. 13) to be engaged by the screws 85 whereby the plate 83 is adjustably secured to the slide 75. The slide 75 is normally and resiliently disposed in its raised position by the spring 86 strained between the pin 76 and the pin 87 on the slide 75 below the recess 81. The stop plate 83 is adapted to engage the pin 88 on the link 20.

The bracket 89 on which the shaft 77 is supported is substantially U-shaped (Fig. 5) and secured to the main frame A. Extending rearwardly from the intermediate

portion 90 of the bracket 89 is the extension 91 on which the cylindrical bearing 92 is secured. Formed in the upper portion of the cylindrical bearing 92 in the rear and 5 front sides thereof are openings 93 and 94 respectively, in alignment with one another through which the rear portion of the setting rod 95 extends, the rear end of the setting rod being provided with a collar 10 96 to limit the forward movement of the rod 95 and the short pin 97 formed on the rod 95 forwardly of the bearing 92 to limit the rearward movement of the rod 95. The rod 95 is adapted to have two setting positions, a forwarding setting where the printing and total taking mechanism operate forwardly and a rearwardly setting where 15 the non-listing operation is automatically performed. For resiliently anchoring the rod 95 in its respective positions, recesses 98 and 99 are formed in the rod 95 spaced from one another a predetermined distance. The recesses 98 and 99 are positioned to cooperate with the plug 100 (Fig. 3) disposed 20 in the bore of the cylindrical bearing 92 and strained between the bottom of said bore and the plug 100 is located the spring 101 by means of which the plug 100 is strained against the rod 95 and consequently 25 when the rod is moved so that the plug 100 engages the recess 99, the rod 95 is anchored in the forward position or non-listing position and when positioned so that the plug 100 engages the recess 98, the rod 95 is anchored 30 in the rear position or position for normal operation of the printing and total taking mechanisms. Mounted on the shaft 77 are the short lever 102 and the long lever 103 which are connected to one another by 35 the plate 104 so that the action of the lever 103 will simultaneously actuate the lever 102. The plate 104 has a forwardly extending portion 105 in which the screw 106 is disposed, such screw 106 contacting with the 40 intermediate portion 90 of the bracket 89 when the levers 102 and 103 are raised and thereby limiting the upward movement of such levers, the screw 106 being adjustable to permit adjusting the upward movement 45 of such levers. For resiliently maintaining the levers 102 and 103 in raised position, the plate 104 is connected by spring 107 with the spring abutment 108 which is secured to the upper end of the cylindrical portion 50 92. On the free end of the short lever 102 is pivotally connected the short pawl 109 and on the shaft 77 adjacent to the short lever 102 is pivotally connected the long pawl 110. The active ends of the pawls 109 and 110 are bent to one side, the active end 55 of the pawl 110 above the active end of the pawl 109 for engagement with the ratchet teeth 80 of the slide 75, the teeth 80 being shown as arranged in pairs, the two upper 60 teeth for coöperation with the pawl 110 and the two lower teeth for coöperation with the pawl 109. For resiliently maintaining the pawls 109 and 110 in engagement with the teeth 80 when the rod 95 is set in forward or non-listing position, the spring 111 is 65 provided connecting the pin 112 of the pawl 109 with the pin 113 on the pawl 110, thereby anchoring the two pawls resiliently against one another, and the spring 114 is provided for anchoring the pin 113 on the 70 pawl 110 with the total taking shaft 32 whereby the pawls 109 and 110 are both resiliently maintained in engaging position with the slide 75. The pawl 110 is provided with a pin 115 adapted to be engaged by 75 the pin 116 on the rod 95 disposed a little forwardly of the pin 97. Thus when the rod 95 is moved in its rearward position or 80 position for normal operation of the printing and total taking mechanism, its pin 116 85 will engage the pin 115 of the pawl 110 and thereby withdraw both pawls 110 and 109 out of engagement with the slide 75 whereby to make the non-listing mechanism inoperative. 90

On the long lever 103 is formed the pin 117 for engagement by the crank sector 30 when moving down in its forward position. From the foregoing, it will be seen that when the rod 95 is drawn out into the outer 95 or non-listing position, the pawls 109 and 110 will be resiliently maintained in engaging position with the slide 75. Assuming a condition where the slide 75 has been released from the pawls 110 and 109, the slide 100 75 maintained in its extreme raised position by the spring 86, and the link 20 with its upper recess 21 engaged by the pin 27, then upon forward movement of the crank sector 30, the lever 29 will first be engaged thereby 105 actuating the lever 28 to shift the link 20 rearwardly and there with the accumulator wheels 15 out of mesh with the teeth 14 so that upon the release of the segments 13, they will be permitted to be positioned by 110 the setting rods 74 and the designation printed with the first item. Then upon the continued downward movement of the crank sector 30, the pin 117 will be engaged thereby depressing the pawl 109 which being in engagement with the lower set of ratchet teeth 80 of the slide 75 will depress such slide 75 one tooth space and snap the upper pawl 110 into engagement with one of the upper 115 ratchet teeth 80 so as to prevent the slide 75 from sliding upward again. Then upon the return movement of the sector 30, the lever 29 again being engaged, the lever 28 will be rocked to draw the link 20 forwardly and thus bring the accumulators 15 into engagement with the teeth 14 and permit such first designation to be accumulated on the accumulator wheels. Then upon passing the second card through the machine, and the second forward movement of the sector 30, the 120 125 130

lever 29 will again be engaged thereby actuating the lever 23 to again move the link 20 rearwardly to withdraw the accumulator wheels 15 out of mesh with the teeth 14 and 5 upon the sector 30 continuing in its forward movement the pin 117 will be engaged to operate the pawl 109 to draw downwardly the slide 75 a second tooth space, the pawl 110 engaging a next higher tooth of the upper 10 set of teeth 80 to anchor the slide 75 from upward movement. When the slide 75 has thus been moved the second tooth space, the stop plate 82 will engage the pin 88 of the link 20 and thereby draw the link 20 downwardly so that its recess 21 will be disengaged from the pin 27, the downward movement being comparatively a short distance so that the lower pin 28 will likewise be out of engagement with the recess 22 of the link 20. Then upon the return movement of the sector 30, its engagement with the lever 29 will not in any way affect the position of the wheels 15, these remaining in the position disengaged from the teeth 14. Then al- 25 though the designation character may be printed with every item, it will not accumulate on the accumulator wheels 15 and so when it is desired to take a total, the designation character may be printed with the 30 total amounts.

When a total card is passed through the machine, as already described, the total taking shaft 32 will be rocked whereupon the pin 41 of the lever 40 will engage the bell 35 crank 33 to rock the same and thereby, through the connection of the link 37 between the arm 35 and the link 20 the link 20 will be drawn into its lower position to permit the pin 28 to enter the recess 22 so that upon the engagement of the lever 29 upon the then ensuing forward movement of the crank sector 30, the actuation of the lever 23 will draw the link 20 forwardly thereby moving the accumulator wheels 15 40 into engagement with the teeth 14 upon the advance movement of the segments 13 so that the designation group of printers may then be positioned by the accumulation of the accumulators 15 which have been on the passage through the machine of the first card 45 of the series. The return movement of the sector 30 will, as formerly, actuate the lever 23 to move the link 20 rearwardly, thereby to withdraw the accumulator wheels 15 out 50 of engagement with the teeth 14 while the accumulator wheels 15 are clear, thereby clearing the accumulator wheels 15 for the next series of cards.

For automatically restoring the non-listing mechanism for the next series, the upper arm 34 of the bell crank 33 is provided with a stop finger 118 which will engage the pawl 110 upon the rocking of the bell crank 33 thereby rocking both the pawls 110 and 55 109 out of engagement with the slide 75 and

permitting the slide 75 to be drawn upwardly by its spring 86.

Instead of repeating the same class or group designating number or designator as each successive card of the group is punched, 70 the first card only of such group may be punched, in the appropriate zone, with the class or group number of the group, while subsequent cards of the group may have different designations punched in said zone. 75 These different designations may be individual to each card or to sub-groups of the cards or otherwise, and are printed along with other items of the cards subsequent to the first card.

With this arrangement, the first card with its group designation is analyzed and the data thereof printed, and also accumulated and thus transferred to the totalizer. The accumulator is then automatically cut out, 80 and the said different designations are printed one after the other in said same zone, but are not accumulated. When, however, a total is taken, the accumulator is permitted to mesh with the sectors, and the one group designation which was transferred to the accumulator from the first card is then transferred from the accumulator to the type sectors and printed with the totals of the items which were added.

It is obvious that various changes and modifications may be made to the details of construction without departing from the general spirit of the invention.

I claim:

1. In a machine of the character described, the combination of means for setting up and printing items; means for accumulating said items; means for printing the total accumulated by the accumulating means; and settable means for automatically rendering the accumulating means inoperative from the time that a single item is accumulated after the setting of the settable means until the next total is printed.

2. In a machine of the character described, the combination of a printing mechanism on which items may be set up; an accumulating means adapted to accumulate a set-up item and automatically omit the accumulation of subsequent items; and means for automatically initiating and causing the printing of the accumulated item after said subsequent items have been omitted.

3. In a machine of the character described, a plurality of printing mechanisms on which items may be set up; means for accumulating the totals of said items and printing the totals; certain of the accumulating means being adapted to automatically omit the accumulation of the items set up between the first item and the next subsequent total.

4. In a machine of the character described, the combination of a group of printers; means for setting up items on said printers; 130

- accumulators adapted to be operatively connected with said printers for accumulating totals of the accumulated items; means adapted to cause the printing of said totals; and settable means adapted to be set for automatically rendering said accumulators inoperative from the time that the first item is accumulated until the next total is printed.
5. In a machine of the character described, the combination of a group of printers; means for setting up items on said printers; accumulators adapted to be operatively connected to said printers for accumulating totals of the accumulated items; means adapted to cause the printing of said totals; and settable means adapted to be set for automatically rendering said accumulators inoperative from the time that the first item is accumulated, after the settable means is set, until the next total is printed.
6. In an accounting machine having a plurality of groups of printers, each group of printers having means for defining the position of said printers for printing individual items, actuating means for actuating said printers into printing position, accumulators to be engaged by said printers to accumulate on said accumulators, means for resetting said accumulators so that said accumulators may define the position of said printers for taking totals, and means for anchoring said accumulators out of accumulating position during one or more normal accumulating periods.
- 25 7. In an accounting machine having a plurality of groups of printers, each group of printers having means for defining the position of said printers for printing individual items, actuating means for actuating said printers into printing position, accumulators to be engaged by said printers to accumulate on said accumulators, means for resetting said accumulators so that said accumulators may define the position of said printers for taking totals, and progressively actuated anchoring means for anchoring said accumulators out of accumulating position on the second actuation of said actuating means, the initial actuation of said actuating means affecting the accumulators whereby the first card of a series may be accumulated but accumulation of all the remaining cards be prevented.
- 30 8. In an accounting machine having a plurality of groups of printers, each group of printers having means for defining the position of said printers for printing individual items, actuating means for actuating said printers into printing position, accumulators to be engaged by said printers to accumulate on said accumulators, means for resetting said accumulators so that said accumulators may define the position of said printers for taking totals, and progressively actuated anchoring means including a slide, ratchet teeth on said slide, pawls for engaging said teeth, means for actuating said pawls to position said slide on the second actuation in anchoring position, the initial actuation not affecting the operation of said accumulators.
- 35 9. In an accounting machine having a plurality of groups of printers, each group of printers having means for defining the position of said printers for printing individual items, actuating means for actuating said printers into printing position, accumulators to be engaged by said printers to accumulate on said accumulators, means for resetting said accumulators so that said accumulators may define the position of said printers for taking totals, progressively actuated anchoring means including a slide, ratchet teeth on said slide, pawls for engaging said teeth, means for actuating said pawls to position said slide on the second actuation in anchoring position, the initial actuation not affecting the operation of said accumulators, and a finger on said resetting means for engaging said pawls to release said slide thereby to permit the restoration of said slide.
- 40 10. In an accounting machine having a plurality of groups of printers, each group of printers having means for defining the position of said printers for printing individual items, actuating means for actuating said printers into printing position, accumulators to be engaged by said printers to accumulate on said accumulators, means for automatically initiating the resetting of said accumulators so that said accumulators may define the position of said printers for taking totals, and means for automatically anchoring said accumulators out of accumulating position during one or more normal accumulating periods, said anchoring means not interfering with the operation of said resetting means.
- 45 11. In an accounting machine having a plurality of groups of printers, each group of printers having means for defining the position of said printers for printing individual items, actuating means for actuating said printers into printing position, accumulators to be engaged by said printers to accumulate on said accumulators, means for resetting said accumulators so that said accumulators may define the position of said printers for taking totals, progressively actuated anchoring means for anchoring said accumulators out of accumulating position on the second actuation of said anchoring means, the initial actuation of said actuating means not affecting the accumulators whereby the first card of a series may be accumulated but accumulation of all the remaining cards be prevented, and means restoring said accumulators.
- 50 12. In an accounting machine having a plurality of groups of printers, each group of printers having means for defining the position of said printers for printing individual items, actuating means for actuating said printers into printing position, accumulators to be engaged by said printers to accumulate on said accumulators, means for resetting said accumulators so that said accumulators may define the position of said printers for taking totals, and progressively actuated anchoring means for anchoring said accumulators out of accumulating position on the second actuation of said anchoring means, the initial actuation of said actuating means not affecting the accumulators whereby the first card of a series may be accumulated but accumulation of all the remaining cards be prevented, and means restoring said accumulators.
- 55 13. In an accounting machine having a plurality of groups of printers, each group of printers having means for defining the position of said printers for printing individual items, actuating means for actuating said printers into printing position, accumulators to be engaged by said printers to accumulate on said accumulators, means for resetting said accumulators so that said accumulators may define the position of said printers for taking totals, and anchoring means including a slide, ratchet teeth on said slide, pawls for engaging said teeth, means for actuating said pawls to position said slide on the second actuation in anchoring position, the initial actuation not affecting the operation of said accumulators.

- of printers having means for defining the position of said printers for printing individual items, actuating means for actuating said printers into printing position, accumulators to be engaged by said printers to accumulate on said accumulators, and means for resetting said accumulators so that said accumulators may define the position of said printers for taking totals, progressively actuated anchoring means for anchoring said accumulators out of accumulating position on the second actuation of said anchoring means, the initial actuation of said actuating means not affecting the accumulators whereby the first card of a series may be accumulated but accumulation of all the remaining cards be prevented, said anchoring means not interfering with the operation of said resetting means.
13. In an accounting machine having a plurality of groups of printers, each group of printers having means for defining the position of said printers for printing individual items, actuating means for actuating said printers into printing position, accumulators to be engaged by said printers to accumulate on said accumulators, means for resetting said accumulators so that said accumulators may define the position of said printers for taking totals, progressively actuated anchoring means for anchoring said accumulators out of accumulating position on the second actuation of said anchoring means, the initial actuation of said actuating means not affecting the accumulators whereby the first card of a series may be accumulated but accumulation of all the remaining cards be prevented, said anchoring means not interfering with the operation of said resetting means, and means for storing said accumulators.
14. In an accounting machine having a plurality of groups of printers, each group of printers having means for defining the position of said printers for printing individual items, actuating means for actuating said printers into printing position, accumulators to be engaged by said printers to accumulate on said accumulators, means for resetting said accumulators so that said accumulators may define the position of said printers for taking totals, progressively actuated anchoring means for anchoring said accumulators out of accumulating position on the second actuation of said anchoring means, the initial actuation of said actuating means not affecting the accumulators whereby the first card of a series may be accumulated but accumulation of all the remaining cards be prevented, a total taking shaft, and connecting means connecting said resetting means with said total taking shaft whereby the actuation of said total taking shaft will actuate said resetting means.
15. In an accounting machine having a plurality of groups of printers, each group of printers having means for defining the position of said printers for printing individual items, actuating means for actuating said printers into printing position, accumulators to be engaged by said printers to accumulate on said accumulators, means for resetting said accumulators so that said accumulators may define the position of said printers for taking totals, means for anchoring said accumulators out of accumulating position, a total taking shaft, a bell crank loosely mounted on said total taking shaft, a fixed arm on said shaft for connecting said bell crank to be actuated with said shaft, and a spring for normally maintaining said bell crank in engagement with said fixed arm, the said resetting means being connected to said bell crank so that the actuation of said total taking shaft will actuate said resetting means.
16. In an accounting machine having a plurality of groups of printers, each group of printers having means for defining the position of said printers for printing individual items, actuating means for actuating said printers into printing position, accumulators to be engaged by said printers to accumulate on said accumulators, means for resetting said accumulators so that said accumulators may define the position of said printers for taking totals, means for anchoring said accumulators out of accumulating position, a total taking shaft, a bell crank loosely mounted on said total taking shaft, a fixed arm on said shaft for connecting said bell crank to be actuated with said shaft, and a spring for normally maintaining said bell crank in engagement with said fixed arm, the said resetting means being connected to said bell crank so that the actuation of said total taking shaft will actuate said resetting means.
17. In an accounting machine having a plurality of groups of printers, each group of printers having means for defining the position of said printers for printing individual items, actuating means for actuating said printers into printing position, accumulators to be engaged by said printers to accumulate on said accumulators, means for resetting said accumulators so that said accumulators may define the position of said printers for taking totals, means for anchoring said accumulators out of accumulating position, a total taking shaft, a bell crank loosely mounted on said total taking shaft, a fixed arm on said shaft for connecting said bell crank to be actuated with said shaft, a spring for normally maintaining said bell crank in engagement with said fixed arm, the said resetting means being connected to said bell crank so that the actuation of said total taking shaft will actuate said resetting means.

taking shaft will actuate said resetting means, said anchoring means not interfering with the operation of said resetting means, and means for restoring said accumulators.

- 5 18. In an accounting machine having a plurality of groups of printers, each group of printers having means for defining the position of said printers for printing individual items, actuating means for actuating 70
10 said printers into printing position, accumulators to be engaged by said printers to accumulate on said accumulators, means for resetting said accumulators so that said accumulators may define the position of said 75
15 printers for taking totals, means for anchoring said accumulators out of accumulating position, a total taking shaft, a bell crank loosely mounted on said total taking shaft, a fixed arm on said shaft for connecting said
20 bell crank to be actuated with said shaft, a spring for normally maintaining said bell crank in engagement with said fixed arm, the said resetting means being connected to said bell crank so that the actuation of said total 80
25 taking shaft will actuate said resetting means, said anchoring means not interfering with the operation of said resetting means, and means for restoring said accumulators. 85

19. In an accounting machine having a 90
30 plurality of groups of printers, each group of printers having means for defining the position of said printers for printing individual items, actuating means for actuating said printers into printing position, accumulators to be engaged by said printers to accumulate on said accumulators, means for resetting said accumulators so that said accumulators may define the position of said 95
35 printers for taking totals, progressively actuated anchoring means including a slide, ratchet teeth on said slide, pawls for engaging said teeth, means for actuating said pawls to position said slide on the second 100
40 actuation in anchoring position, the initial actuation not affecting the operation of said accumulators, a total taking shaft, and connecting means connecting said resetting means with said total taking shaft whereby the actuation of said total taking shaft will 105
45 actuate said resetting means. 110

20. In an accounting machine having a plurality of groups of printers, each group of printers having means for defining the position of said printers for printing individual items, actuating means for actuating said printers into printing position, accumulators to be engaged by said printers to accumulate on said accumulators, means for resetting said accumulators so that said accumulators may define the position of said 115
50 printers for taking totals, progressively actuated anchoring means including a slide, ratchet teeth on said slide, pawls for engaging said teeth, means for actuating said pawls to position said slide on the second 120
55 actuation in anchoring position, the initial actuation not affecting the operation of said accumulators, a total taking shaft, and connecting means connecting said resetting means with said total taking shaft whereby the actuation of said total taking shaft will 125
60 actuate said resetting means. 130

actuation in anchoring position, the initial actuation not affecting the operation of said accumulators, a total taking shaft, connecting means connecting said resetting means with said total taking shaft whereby the actuation of said total taking shaft will actuate said resetting means, and a finger on said bell crank for engaging said pawls to release said slide thereby to permit the restoration of said slide. 75

21. In an accounting machine having a plurality of groups of printers, each group of printers having means for defining the position of said printers for printing individual items, actuating means for actuating said printers into printing position, accumulators to be engaged by said printers to accumulate on said accumulators, means for resetting said accumulators so that said accumulators may define the position of said 80
85 printers for taking totals, progressively actuated anchoring means including a slide, ratchet teeth on said slide, a shaft, a lever on said shaft, pawls for engaging said teeth, one of said pawls being pivotally connected to said lever and the other pawl pivotally connected to said shaft, a spring for resiliently connecting the pawls to one another, a second spring for resiliently maintaining the pawls in engagement with said ratchet 90
95 teeth, a crank sector, a second lever connected to said first lever, said crank sector being disposed to actuate said second lever thereby to actuate said first lever to in turn actuate said slide, the second actuation of said second 100
105 lever by said sector upon the second of a series of cards being analyzed, positioning said slide in anchoring position, the initial actuation not affecting the operation of said accumulators. 110

22. In an accounting machine having a group of printers, accumulators for co-operating with said printers, shifting means operatively connected to said accumulators for bringing said accumulators into or out of engagement with said printers, rocking means having two active ends for connecting said shifting means, one of said active ends operative to shift said shifting means to bring said accumulators into engagement 115
115 with said printers for accumulation, and the other of said active ends operative for shifting said shifting means to bring said accumulators into engagement with said printers for taking a total, actuating means 120
120 for actuating said rocking means, and means for anchoring said shifting means out of engagement with said rocking means. 125

23. In an accounting machine having a group of printers, accumulators for co-operating with said printers, a shifting link operatively connected to said accumulators for bringing said accumulators into or out of engagement with said printers, rocking means having an upper and a lower active 130

end, the upper active end being operative to connect said shifting link for shifting the same to bring said accumulators into engagement with said printers for accumulation, the lower active end being operative to connect said shifting link for shifting the same to bring said accumulators into engagement with said printers for taking a total, actuating means for actuating said rocking means, and means for anchoring said rocking means out of engagement with said shifting link.

24. In an accounting machine having a group of printers, accumulators for coöperating with said printers, a shifting link operatively connected to said accumulators for bringing said accumulators into or out of engagement with said printers, rocking means having an upper and a lower active end, the upper active end being operative to connect said shifting link for shifting the same to bring said accumulators into engagement with said printers for accumulation, the lower active end being operative to connect said shifting link for shifting the same to bring said accumulators into engagement with said printers for taking a total, actuating means for actuating said rocking means, positive anchoring means for positively anchoring said shifting link out of engagement with the upper active end of said rocking means, and means for resiliently maintaining said shifting link in raised position out of contact with said lower active end, the positive anchoring means anchoring said shifting link just above said lower active end whereby accumulation will be prevented.

25. In an accounting machine having a group of printers, accumulators for coöperating with said printers, a shifting link operatively connected to said accumulators for bringing said accumulators into or out of engagement with said printers, rocking means having an upper and a lower active end, the upper active end being operative to connect said shifting link for shifting the same to bring said accumulators into engagement with said printers for accumulation, the lower active end being operative to connect said shifting link for shifting the same to bring said accumulators into engagement with said printers for taking a total, actuating means for actuating said rocking means, positive anchoring means for positively anchoring said shifting link out of engagement with the upper active end of said rocking means, means for resiliently maintaining said shifting link in raised position out of contact with said lower active end, the positive anchoring means anchoring said shifting link just above said lower active end whereby accumulation will be prevented, and a total taking means for drawing down said shifting link into con-

tact with said lower active end against the tension of said resilient means.

26. In an accounting machine having a group of printers, accumulators for coöperating with said printers, a shifting link operatively connected to said accumulators for bringing said accumulators into or out of engagement with said printers, rocking means having an upper and a lower active end, the upper active end being operative to connect 70 said shifting link for shifting the same to bring said accumulators into engagement with said printers for accumulation the lower active end being operative to connect 80 said shifting link for shifting the same to bring said accumulators into engagement with said printers for taking a total, actuating means for actuating said rocking means, positive anchoring means for positively anchoring said shifting link out of 85 engagement with the upper active end of said rocking means, means for resiliently maintaining said shifting link in raised position out of contact with said lower active end, the positive anchoring means anchoring 90 said shifting link just above said lower active end whereby accumulation will be prevented, a total taking means for drawing down said shifting link into contact with said lower active end against the tension 95 of said resilient means, and means for re-storing said positive anchoring means.

27. In an accounting machine having a group of printers, accumulators for coöperating with said printers, a shifting link 100 operatively connected to said accumulators for bringing said accumulators into or out of engagement with said printers, rocking means having an upper and a lower active end, the upper active end being operative 105 to connect said shifting link for shifting the same to bring said accumulators into engagement with said printers for accumulation, the lower active end being operative to connect said shifting link for shifting the 110 same to bring said accumulators into engagement with said printers for taking a total, actuating means for actuating said rocking means, positive anchoring means for positively anchoring said shifting link 115 out of engagement with the upper active end of said rocking means, means for resiliently maintaining said shifting link in raised position out of contact with said lower active end, the positive anchoring 120 means anchoring said shifting link just above said lower active end whereby accumulation will be prevented, a total taking means for drawing down said shifting link into contact with said lower active end 125 against the tension of said resilient means, and means for progressively setting said positive anchoring means by two actuations so that the first card of a series may have a record accumulated and only upon the 130

second actuation when a second card of the series is analyzed the anchoring means will be properly set.

28. In an accounting machine having a group of printers, accumulators for coöperating with said printers, a shifting link operatively connected to said accumulators for shifting said accumulators into or out of engagement with said printers, rocking means having an upper and a lower active end, the upper active end being operative to connect said shifting link for shifting the same to bring said accumulators into engagement with said printers for accumulation, the lower active end being operative to connect said shifting link for shifting the same to bring said accumulators into engagement with said printers for taking a total, actuating means for actuating said rocking means, means for anchoring said shifting link, and means whereby said anchoring means may either be set into operation for non-accumulation or out of operation for normal operation of the machine.
29. In an accounting machine having a group of printers, accumulators for coöperating with said printers, a shifting link operatively connected to said accumulators for bringing said accumulators into or out of engagement with said printers, rocking means having an upper and a lower active end, the upper active end being operated to connect said shifting link for shifting the same to bring said accumulators into engagement with said printers for accumulation, the lower active end being operated to connect said shifting link for shifting the same to bring said accumulators into engagement with said printers for taking a total, a crank sector for actuating said rocking means, a slide, resilient means for maintaining said slide in position, a stop plate on said slide, a pin on said link for engagement by said slide, ratchet teeth on said slide, a shaft, a lever on said shaft, a pawl pivotally mounted on said shaft, a second pawl pivotally mounted on the end of said lever, the active ends of said pawls being operatively disposed to engage said ratchet teeth, a second lever on said shaft connected to said first lever, said crank sector being adapted to engage said second lever to rock the pawl connected on said first lever thereby to actuate said slide, a spring for normally maintaining said levers in raised position, a spring for normally maintaining said pawls adjacent to one another, a spring for resiliently maintaining both said pawls in engagement with said ratchet teeth, the actuation of said slide by said sector being progressive, the first actuation drawing the slide down one tooth, the second actuation drawing down the slide a second tooth, so that said stop plate strikes said pin

and draws down said link out of engagement with said upper active end whereby the accumulators will be prevented from being positioned for accumulation.

30. In an accounting machine having a plurality of groups of printers, each group of printers having means for defining the position of said printers for printing individual items, actuating means for actuating said printers into printing position, accumulators to be engaged by said printers to accumulate on said accumulators, means for resetting said accumulators so that said accumulators may define the position of said printers for taking totals, progressively actuated anchoring means including a slide, ratchet teeth on said slide, a shaft, a lever on said shaft, pawls for engaging said teeth, one of said pawls being pivotally connected to said lever and the other pawl, pivotally connected to said shaft, a spring for resiliently connecting the pawls to one another, a second spring for resiliently maintaining the pawls in engagement with said ratchet teeth, a crank sector, a second lever connected to said first lever, said crank sector being disposed to actuate said second lever thereby to actuate said first lever to in turn actuate said slide, the second actuation of said second lever by said sector upon the second of a series of cards being analyzed, positioning said slide in anchoring position, the initial actuation not affecting the operation of said accumulators, and means for anchoring said pawls out of engagement with said slide thereby to permit the normal operation of said machine.
31. In an accounting machine having a group of printers, accumulators for coöperating with said printers, shifting means operatively connected to said accumulators for bringing said accumulators into or out of engagement with said printers, rocking means having two active ends for connecting with said shifting means, one active end for shifting said shifting means to bring said accumulators into engagement with said printers for accumulation, and the other of said active ends for shifting said shifting means to bring said accumulators into engagement with said printers for taking a total, anchoring means for anchoring said shifting means out of engagement with said first mentioned active end to prevent accumulation, means for progressively drawing said anchoring means into anchoring position, and setting means for setting said drawing means either into or out of connection with said anchoring means to operate the same.

32. In an accounting machine having a group of printers, accumulators for coöperating with said printers, shifting means operatively connected to said accumulators for bringing said accumulators into or out of

engagement with said printers, rocking means having two active ends for connecting with said shifting means, one active end for shifting said shifting means to bring 5 said accumulators into engagement with said printers for accumulation, and the other of said active ends for shifting said shifting means to bring said accumulators into engagement with said printers for taking a 10 total, anchoring means for anchoring said shifting means out of engagement with said first mentioned active end to prevent accumulation, means for progressively drawing said anchoring means into anchoring position, setting means for setting said drawing means either into or out of connection with said anchoring means to operate the same, said setting means comprising a shiftable rod, a pin on said drawing means, and a 20 second pin on said rod for engaging said first pin to bring said drawing means either into or out of engagement with said anchoring means.

33. In an accounting machine, the combination with a plurality of groups of printers, each group of printers having means for defining the position of said printers for printing individual items, actuating means for actuating said printers into printing position, accumulators to be engaged by said printers to accumulate on said accumulators, means for resetting said accumulators so that said accumulators may define the position of said printers for taking totals, one of said 30 groups of printers being used for printing designation characters, and means for anchoring the accumulators of said designation group of printers out of accumulating position.

40 34. In an accounting machine, the combination with a plurality of groups of printers, each group of printers having means for defining the position of said printers for printing individual items, actuating means for actuating said printers into printing position, accumulators to be engaged by said printers to accumulate on said accumulators, means for resetting said accumulators so that said accumulators may define the position of said 45 printers for taking totals, one of said groups of printers being used for printing designation characters, progressive anchoring means for anchoring the accumulators of said designation group of printers out of accumulating position after the record of a first card of a series has been accumulated, and actuating means for actuating said anchoring means into anchoring position upon the second actuation for a series of record 55 cards, the initial actuation not affecting the operation of the accumulators.

35. In an accounting machine, the combination with a plurality of groups of printers, each group of printers having means for defining the position of said printers for

printing individual items, actuating means for actuating said printers into printing position, accumulators to be engaged by said printers to accumulate on said accumulators, means for resetting said accumulators 70 so that said accumulators may define the position of said printers for taking totals, one of said groups of printers being used for printing designation characters, progressive anchoring means for anchoring the accumulators of said designation group of printers out of accumulating position after the record of a first card of a series has been accumulated, actuating means for actuating said anchoring means into anchoring 75 position upon the second actuation for a series of record cards, the initial actuation not affecting the operation of the accumulators, a total taking shaft, and connecting means connecting said resetting means with 80 said total taking shaft whereby the actuation of said total taking shaft will actuate said resetting means to reset the accumulators of all the groups of printers including the designation group so that said accumulators may define the position of said printers when taking the total.

36. In a machine of the character described, the combination of a printing mechanism on which items may be set up; an accumulator adapted to effect the accumulation of a set-up item and to automatically become inoperative during the subsequent setting up of items; and an initiating means for causing the total-taking of said set-up 95 item after said subsequent setting up.

37. In a machine of the character described, the combination of a printing mechanism on which items may be set up; an accumulator adapted to effect the accumulation of a set-up item and to automatically become inoperative during the subsequent cycle of operation of the machine; and a single initiating means for causing the total-taking of said set up item after said subsequent operation.

38. In a machine of the character described, the combination of a printing mechanism on which items may be set up; an accumulator adapted, when operative, to 115 effect the accumulation of a set-up item; means put into operation by the said accumulation for rendering the accumulator inoperative and preventing subsequent accumulations; initiating means for causing 120 total-taking; and means put into operation by said initiating means for rendering operative the inoperative-rendered accumulator.

39. In a machine of the character described, the combination of a printing mechanism on which items may be set up; an accumulator adapted, when operative, to effect the accumulation of a set up item; means put into operation by the said ac- 125

cumulation for rendering the accumulator inoperative; total-taking mechanism; and means for rendering operative the inoperative-rendered accumulator and actuating 5 the total-taking mechanism.

40. In a machine of the character described, the combination of a printing mechanism on which items may be set up; an accumulator adapted, when operative, to 10 effect the accumulation of a set-up item; automatic means for rendering the accumulator inoperative; total-taking mechanism; and means for rendering operative the inoperative-rendered accumulator and actuating 15 the total-taking mechanism.

41. In a machine of the character described, the combination of a printing mechanism on which items may be set up; an 20 accumulator means adapted, when operative, to effect the accumulation of a set-up item; automatic means put into operation by the said accumulation for rendering the accumulator inoperative and preventing subsequent accumulations; total-taking 25 mechanism; and means for rendering operative the inoperative-rendered accumulator and actuating the total-taking mechanism.

42. In a machine of the character described, the combination of a printing mechanism on which items may be set up; an accumulator means adapted, when operative, to effect the accumulation of a set-up item; automatic means put into operation by the 30 said accumulation for rendering the accumulator inoperative and preventing subsequent accumulations; total-taking mechanism; initiating means for causing said mechanism to take a total; and means put into operation by said initiating means, 35 when initiating total-taking, for rendering operative the inoperative-rendered accumulator. 40

43. In a machine of the character described, the combination of means for setting up and printing items; means for accumulating said items; means for automatically rendering the accumulating means inoperative; and means for automatically initiating the taking of a total and rendering operative the inoperative-rendered 45 accumulator. 50
